UNITED STATES PATENT OFFICE.

JAMES H. WILLIAMS, OF NORWALK, OHIO, ASSIGNEE TO UNITED PIANO CORPORATION, OF NORWALK, OHIO, A CORPORATION OF NEW YORK.

KEY-LEVELING DEVICE.

Application filed June 9, 1925. Serial No. 35,961.

This invention relates to new and useful improvements in leveling devices, and particularly to devices for leveling the keys of grand or other pianos.

5 The keys of a piano are disposed on a keyboard frame, with their inner ends resting on a strip of felt, which extends beneath all of the keys. This felt strip varies in thickness, with the result that certain of the keys 10 are elevated or depressed to an extent as to dispose their ivory-covered ends out of the horizontal plane of the remaining keys. It is therefore necessary to treat these certain keys so that their ivory-covered ends all lie 15 in a common plane, whereby to present a neat appearance, and not interfere with the manipulation of the keys.

Heretofore, in leveling the keys of a piano, they were placed on a table, or within a 20 piano, and then the action positioned so as to rest on the inner ends of the keys. When it was found that ivoried ends certain of the keys were not level, or in the plane of the others, the action was removed, the unlevel keys withdrawn, and building-up washers placed on the fulcrum pins, or the keys trimmed on their under sides, as found necessary. The keys were then restored to their 25 places and the action again placed in position, this operation being repeated until the entire key-board were found to be level. This inserting and removing of the action resulted in a great loss of time and consequent increase in expense.

30 It is therefore the object of the present invention to provide means for holding the keys in the positions they will assume when assembled with the action, without it being necessary to place the action thereon, so that they may be readily removed and replaced 35 during the key leveling operation.

Other objects and advantages will be apparent from the following description when taken in connection with the accompanying drawing.

In the drawing:

Figure 1 is a side elevation of the invention in operative relation to a piano key.

Figure 2 is a perspective view of one of the weighted levers removed from the rail.

Figure 3 is a top plan view of several keys and the weighted levers resting thereon.

Referring particularly to the accompanying drawing, 10 represents the top of a work table, which is adapted to support the base

11, on which the keys 12 are mounted. On the rear portion of the table top there is disposed a depressing mechanism comprising a rail 13, which is substantially L-shaped in cross section, and secured to the upper edge face of the vertical portion of said rail, by means of the screws 14, are the forwardly extending bifurcated members 15, within each of which is pivotally mounted the end of a lever 16. The other end of the lever 16 is fitted in a longitudinal groove 17, formed in the lower face of a weighted block 18. The forward end of the block 18 is beveled, as shown, and the corresponding end of the lever 16 is beveled in conformity thereto, the lower portion of the free end of the lever being underbeveled, as shown at 19, whereby to permit easy passage of a key therebeneath, without the necessity of manually lifting the lever.

The weight of each of the levers 16 is sufficient to depress the key upon which it rests, to the same degree to which it will be depressed by the piano action, so that the operator may, at a glance, determine which of the keys require manipulation, to provide a level keyboard. Such keys may then be readily removed, raised by placing washers on the fulcrum pins, or lowered by trimming, and quickly restored to position.

It is to be further understood that the base 11 is adapted to be engaged beneath the hooks 20, at one side, and held on the table 10 by means of the clamps 21, at the other side.

The rail 13 is maintained against being moved out of its proper position, when a key is restored in position after having been treated, by the adjustable stops 22, held on the table 10 by means of the bolts 23, and winged nuts 24. Sometimes, when a key is inserted its inner end strikes the free end of the corresponding lever 16, without causing the lever to rise, with the result that, were the stops 22 not positioned to hold the rail, the key would act on the lever to move the rail out of its proper position.

In the operation of the device, the rail 13, with its weighted levers 16, is placed on the table against the stops 22. The key-board frame, with the keys thereon, is placed on the table and moved toward the rail so that the inner ends of the keys engage beneath the beveled ends of said levers to lift the same, whereby the levers will ultimately rest

on the inner ends of the keys. The weight of the levers 16 corresponds, approximately, to the weight of the piano action, when normally resting thereon, in a piano. Due to the variance in thickness of the felt, at different points along its length, certain of the keys will be depressed more or less than the major portion of the key-board. The operator observes which of the keys are out of the plane to which said keys are to be brought, by the use of a straight-edge, and beginning at one end of the key-board, removes the first of the keys which are out of alinement. Should this key stand above the plane of the keys, the operator trims its lower face, at the point adjacent the pivot pin opening, and then restores it to its place, again observing whether or not sufficient has been trimmed off to bring its outer end to the proper level. Should the key be disposed below the plane of the other keys, the operator builds it up by placing washers on the pivot pin of the key-board frame. Each key, which rises above, or lies below the desired plane of the key-board is removed and lowered by trimming, or built up by washers, until all of the keys have been brought to the desired level, that is the ivored-ends, or playing ends of the keys.

What is claimed is:

1. A device for use in leveling the keys of a piano before they are applied to a piano action, including a base for supporting the frame of a piano key-board apart from the piano action, and means associated with the base for holding the inner ends of the keys in the depressed position, on the frame, corresponding to that normally brought about by the piano action assembly.
2. A device for use in leveling the keys of a piano before they are applied to a piano action including a base for supporting the frame of a piano key-board outside of a piano, and means associated with the base for gravitation upon the inner ends of the keys to hold said ends in the depressed position on the frame corresponding to that normally brought about by the piano action assembly.
3. A device for leveling the keys of a piano before they are assembled with a piano action including a base for supporting the frame of a piano key-board, apart from the piano action, and means associated with the base for gravitation upon the inner ends of the keys for holding said ends in the depressed position on the frame normally brought about by the piano action assembly.
4. A device for use in leveling the keys of a piano before they are assembled with a

piano action including a base for supporting the frame of a key-board apart from the piano action, and means associated with the base and operable upon the inner ends of the keys for holding the same in the depressed position on the frame normally brought about by the piano action assembly. 65

5. A device for use in leveling the keys of a piano before they are applied to a piano action including a base for supporting the frame of a key-board apart from the piano action, a rail on the base, and a series of levers on the rail adapted to engage with and hold the inner ends of the keys in the depressed position on the frame normally brought about by the piano action assembly. 70

6. A device for use in leveling the keys of a piano before they are applied to a piano action including a base for supporting the frame of a key-board apart from the piano action, a rail mounted on the base, and a gravity lever pivoted on the rail and adapted to engage and depress the inner end of a key to a degree normally brought about by the piano action assembly. 75

7. A device for use in leveling the keys of a piano before they are applied to a piano action including a base for supporting the frame of a key-board apart from the piano action, a rail on the base, and gravity levers pivoted to the rail and adapted, when said frame is supported on said base, to engage the inner ends of the keys and depress them into their normal action depressed position. 85

8. A device for use in leveling the keys of a piano before they are applied to a piano action including a base for supporting the frame of a key-board apart from a piano and the action thereof, means for clamping the frame on the base, and means for depressing the inner ends of the keys, when said frame is supported on said base, into a position on the frame corresponding to that normally brought about by the piano 100 action assembly. 105

9. A device for use in leveling piano keys apart from a piano and the action thereof comprising a base for supporting the frame of a key-board, clamps for engagement with the frame and base, and means for depressing the inner ends of the keys, when said frame is supported on said base, into a position on the frame corresponding to that normally brought about by the piano action 110 assembly. 115

In testimony whereof, I affix my signature.

JAMES H. WILLIAMS.
